UNITED STATES PATENT OFFICE.

WILLIAM W. BLODGETT AND JOHN H. SMITS, OF BROOKFIELD CENTRE, WIS.

CULTIVATOR.

SPECIFICATION forming part of Letters Patent No. 223,982, dated February 3, 1880.

Application filed October 20, 1879.

To all whom it may concern:

Be it known that we, WM. W. BLODGETT and JOHN H. SMITS, of Brookfield Centre, in the county of Waukesha, and in the State of 5 Wisconsin, have invented certain new and useful Improvements in Cultivators; and we do hereby declare that the following is a full, clear, and exact description thereof.

Our invention relates to cultivators; and it 10 consists in devices for regulating the dip and depth of the plows, as will hereinafter be fully described.

In the drawings, Figure 1 is a perspective of a cultivator as improved by us; and Fig. 15 2 is a side view of one of the rear corners, with part broken away.

A A are the plow-beams, and B is the draft-bar. This draft-bar passes between the front ends of the plow-beams and back to the base-bar, where it is secured, and is provided with 20 a head-block, B', which fits over its front end, and which has a vertical hole through it for the standard b of a caster-wheel to play in. The standard b is perforated transversely to 25 receive a pin or bolt, b', for holding it in proper adjustment, and is bifurcated at its top to receive a lever, E, which is pivoted thereto.

The front end of lever E is connected with a clevis, D, which projects up from the head-block B, by a chain, d', and the other extends back as far as the base-bar, and in a position 30 to be caught by the hook E'.

A bent axle, F, is secured in suitable bearings on the under side of the plow-beams, and 35 passes through an S-lever, F', which is squared onto it. This lever is operated by a bell-crank lever, G, and chains f f', passing down from either side of its pivot.

Projecting up from the axle F we provide 40 curved standards H, having perforations h h for engagement with the bolts K K. These standards pass through brackets I, also perforated.

A toggle-lever, K', is pivoted to the longitudinal center of the base-bar C, from which 45 extend, on each side, the bolts K K. The proper elevation is given by passing the bolt

b' through the standard b. The bolts K K are then withdrawn and the axle turned, by means of the levers F' and G, until the wheels 50 have been sufficiently raised or lowered. The bolts K K are then forced out through the standards by the toggle-lever K', which locks them in place. The machine is now ready.

If at any time it becomes necessary to give 55 the plows more dip, the driver has only to operate the lever K' to withdraw the bolts, and with the other hand adjust the wheels by manipulating the bell-crank lever G.

When it is desired to decrease the dip or 60 clear obstructions, the lever E is brought into requisition, a pressure on the rear end of which will elevate the front of the machine; or the plows may be held entirely out of the ground by catching the free end of lever E 65 under the hook E' and depressing and locking the wheels in their lowest position.

The clevis-bar D is made to project above the head-block, so that the draft will not have a tendency to lift the plows out of the ground. 70

We are aware that various devices have been patented for raising and lowering or regulating the height of the teeth or plows with relation to the wheels in cultivators; and therefore we do not claim such broadly; but 75

What we claim is—

1. The combination, with the wheels and bent axle, of the levers F' and G, connected as described.

2. The combination, in a cultivator, of the 80 wheels, bent axle, curved standards H H, and levers F' G, as set forth.

3. The combination of the wheels, bent axle, curved standards, brackets I, and locking mechanism K K' K.

In testimony that we claim the foregoing we have hereunto set our hands this 6th day of October, 1879.

W. W. BLODGETT.
JOHN H. SMITS.
